UNITED STATES PATENT OFFICE.

ARCHER A. LANDON, OF BUFFALO, NEW YORK, ASSIGNOR TO AMERICAN RADIATOR COMPANY, OF CHICAGO, ILLINOIS, A CORPORATION OF NEW JERSEY.

CONTROLLING MECHANISM FOR ROTARY CASTING-MACHINES.

1,383,729.

Specification of Letters Patent. Patented July 5, 1921.

Application filed October 18, 1916. Serial No. 126,332.

To all whom it may concern:

Be it known that I, ARCHER A. LANDON, a citizen of the United States, residing at Buffalo, Erie county, in the State of New York, have invented certain new and useful Improvements in Controlling Mechanism for Rotary Casting-Machines, of which the following is a full, clear, and exact specification.

10 My invention relates to means for controlling the movement of a movable member or carrier, and the same has for its object more particularly to provide means to control the movement of the carrier of a revoluble casting machine in such a manner that the mold supports which are mounted upon the carrier may be properly positioned to permit of the loading or unloading of the molds thereon or to permit of the performing of 20 any operation necessary or incidental to the casting operation.

One of the objects of the invention is to provide controlling means for arresting the movement of the carrier and holding it stationary in predetermined positions.

Another object is to provide controlling means which will operate to gradually retard the movement of the carrier and then arrest the movement of the same.

30 Another object is to provide automatically operating means for controlling the movement of the carrier.

Another object is to provide means for controlling the movement of the carrier 35 which means will be actuated by the carrier.

Another object is to provide fluid controlled means for controlling the movement of the carrier.

40 Another object is to provide means for arresting the movement of the carrier at any time.

Other objects will in part be obvious and in part pointed out hereinafter.

45 To the attainment of the aforesaid objects and ends my invention consists in the novel details of construction, and in the combination, connection and arrangement of parts hereinafter more fully described and 50 then pointed out in the claims.

In the accompanying drawings showing an illustrative embodiment of the invention—

55 Figure 1 is a side view of a portion of a rotary casting machine showing a control-

ling mechanism embodying my invention certain of the parts being shown partly broken away and in section;

Fig. 2 is a similar view, on an enlarged scale, showing the parts of the controlling mechanism occupying different positions, and

Fig. 3 is an end view.

By way of illustration the controlling means is shown in connection with a revoluble casting machine of the type shown and described in my co-pending application, Serial No. 788,050, filed September 4, 1913. This type of machine comprises a revoluble carrier mounted in a vertical position and having mounted thereon a plurality of mold supports. The carrier is intermittently rotated to bring the supports successively into a plurality of positions to enable the casting operations to be performed in a substantially constant manner. At the first position of rest of the carrier the prepared mold is placed upon the mold support, at the second position of rest the molten metal is poured into the mold, and at the third position of rest the mold containing the casting is removed from the mold support.

Referring to the drawings the revoluble carrier comprises a hub 10 mounted upon a rotatable, horizontal shaft 11 and having a plurality of radially extending arms or spokes 12 provided adjacent their outer ends, with laterally projecting studs 13 upon which are pivotally mounted suitable mold supports 13'. The outer ends of the spokes 12 are preferably bifurcated and carry rollers 14, 14', 14'', etc., rotatably mounted upon axles 15.

Supported upon the floor are supports 16, 16, and upon their upper surfaces are secured brackets 17, 17 having bearings 18, 18 within which the trunnions 19, 19 of a vertically disposed cylinder 20 are journaled. Working within the cylinder is a piston 21 carried by a piston rod 22 the outer end of which is provided with a seat 23 adapted to be engaged by the rollers 14, 14', etc., on the spokes 12 for a purpose hereinafter described.

At its lower or inner end the cylinder 20 is provided with a port 24 communicating with one end of a conduit 25 having its other end communicating with a hollow casting 26 secured to one of the trunnions 19 and rotatable therewith. A pipe 27 lead-

110

ing from a suitable source of fluid supply also communicates with the hollow casting 26, being held in connection therewith to permit rotation of the hollow casting with respect to the pipe 27 while maintaining a fluid tight joint therewith. The fluid, which is preferably water, is maintained under a pressure just sufficient to raise the piston 21 and piston rod 22 when the seat 23 at the outer end of the piston rod is free from engagement with the rollers 14, 14', etc. Located in the conduit 25 is a valve 28 to control the flow of fluid to and from the cylinder 20. Secured to the outwardly extending end of the valve stem 29 is a lever 30, carrying a weight 31 adjacent its free end, and an arm 32 connected by a link 33 with a lever 34 pivotally secured to the upper or outer end of the cylinder 20. Operatively connected to the lever 34 and extending upwardly therefrom is a cam 35 which is normally in the path of the rollers 14, 14', etc. The valve 28 is normally held in its open position by the weighted lever 30. As the revoluble carrier rotates the rollers 14, 14', etc., will be successively brought into engagement with the cam 35 and, when any one of the rollers engages the cam, the cam will be forced to move to the left, as seen in Fig. 2, thereby depressing lever 34, link 33 and arm 32 whereby the valve 28 will be partially closed. When the roller moves out of engagement with the cam the weighted lever 30 will open the valve and at the same time return the arm 32, link 33, lever 34 and cam 35 to their normal positions so that the cam 35 will be in readiness to be engaged by the next one of the rollers 14, 14', etc. Secured to the upper surfaces of the supports 16, 16, and at a suitable distance from the brackets 17, 17, are brackets 36, 36 supporting an oscillating lever 37 having the portion thereof in rear of the point of support inclined upwardly relatively to the portion in front of the point of support. Pivotally mounted upon the forward end of the lever 37 is a member 38 the upper end of which, when the forward end of the lever 37 is in its raised position as shown in Fig. 2, is adapted to be engaged by the rollers 14, 14', etc., and serves as a stop to arrest the movement of the carrier. Between the upper end of the member 38 and the lever 37 is a compression spring 39 which will be compressed when the upper end is engaged by a roller thereby acting as a buffer and insuring a yielding inward movement of the member 38 to prevent undue shock as the carrier is brought to rest. Outward movement of the member 38 due to the spring 39 is limited by a bolt 40. Pivotally secured to the upper end of the member 38 is one end of a link 42 having its other end pivotally connected to a lever

43 oscillatingly mounted between the supports 16, 16. A link 44 has one of its ends pivoted to the lever 43, and at its other end it is provided with a slot 45 engaging a lug 46 on the cylinder 20 and below the trunnions 19, 19.

The lever 37 is held in its raised position by means of a latch 41 pivotally mounted between the supports 16, 16 and engaging the lower end of the member 38. Upon moving the latch 41 out of engagement with the member 38, the forward end of the lever 37 will drop a sufficient distance to carry the member 38 out of the path of the rollers 14, 14', etc., and, at the same time, the rear end of the lever 37 will be raised into the path of the rollers, as shown in Fig. 2.

The operation is as follows:—

Assuming the parts of the apparatus to be in the positions shown in Fig. 1, in which positions the revoluble carrier is at rest, if it is desired to permit the carrier to rotate, the latch 41 is actuated to free it from engagement with the member 38 thereby allowing the forward end of the lever 37 to drop and the rear end thereof to rise, as shown in Fig. 2. As the upper end of the member 38 is moved out of contact with the roller 14² with which it was in engagement the spring 39 will expand until the outward movement of the member 38 is checked by the bolt 40. This outward movement of the member 38 will cause a corresponding movement of the link 44 whereby the outer end of the slot 45 will be moved from its engagement with the lug 46 as a consequence of which the cylinder 20 will be free to oscillate upon its trunnions 19, 19. As soon as the roller 14² is freed from engagement with the member 38 the carrier will commence to rotate and the piston 21 will be forced downwardly into the cylinder 20 by the pressure of the roller 14 which engages the seat 23 on the end of the piston rod 22, the fluid within the cylinder being forced out through the port 24, and conduit 25 into the pipe 27, the valve 28 being open. During the downward movement of the piston and piston rod, the seat 23 will be maintained in engagement with the roller 14 as the cylinder is permitted to oscillate upon its trunnions 19, 19, whereby the outer end of the piston rod is allowed to follow the arc of travel of the roller 14.

As the carrier continues to rotate the roller 14² will engage the rear end of the lever 37, which is now in its raised position, and will depress the same thereby raising the forward end of the lever to bring the upper end of the member 38 into the path of the roller 14' and at the same time permitting the latch 41 to engage the lower end of the member 38 to hold it in raised position. As the carrier rotates still farther the roller 14²

14 will engage the cam 35 and force the same to move to the left. This movement of the cam 35 will move the lever 34, link 33 and arm 32 to partially close the valve 28, and at 5 the same time will raise the weighted end of lever 30. The partial closing of the valve 28 serves to lessen the flow of fluid from the cylinder as a result of which the downward movement of the piston 21 will be 10 checked and the rotation of the carrier will be retarded, whereby the roller 14' will be prevented from engaging the upper end of the member 38 with undue force. As the roller 14' engages the member 38 the spring 15 39 will be compressed to yieldingly bring the carrier to a position of rest without shock and the inward movement of the upper end of the member 38, due to the compression of the spring, will cause a corresponding 20 movement of the link 44 through the link 42 and lever 43. As the link 44 moves inward the outer end of the slot 45 will engage the lug 46 on the cylinder 20 and will cause the cylinder to swing upon its trunnions 19, 19 to an extent sufficient 25 to carry the seat 23 on the piston rod 22, and also the cam 35, out of engagement with the roller 14. As the cam is freed from engagement with the roller the weighted 30 lever 30 will restore the arm 32, link 33, lever 34 and cam 35 to their normal positions relatively to the cylinder, and at the same time the movement of the lever 30 will open the valve 28 thus permitting fluid to 35 flow freely into the cylinder. As the seat 23 on the piston rod 22 is now free from engagement with the roller 14 the fluid entering the cylinder by way of the port 24 will raise the piston, and the seat 23 will 40 thus be brought into engagement with the roller immediately following the roller 14.

When it is desired to rotate the carrier another step, the latch 41 is again withdrawn from its operative or lever holding position 45 and the above described operation is repeated.

In order to permit the revoluble carrier to be stopped at any time in case of emergency, the weighted lever 30 may be raised 50 to close the valve 28 by a cord or the like 47. The closing of the valve will shut off the flow of fluid from the cylinder 20 thereby preventing the piston 21 from continuing its downward movement as a result of 55 which the carrier will be brought to rest by reason of the fact that one of the rollers 14, 14', etc, is in engagement with the seat 23 on the end of the piston rod 22.

Having thus described my said invention, 60 what I claim and desire to secure by Letters Patent is:—

1. In a machine of the character described, the combination of a movable carrier, with a member adapted to be engaged by said carrier and to be moved thereby, means con-

trolled by said carrier for retarding the movement of said member after it has been engaged by said carrier, and means for arresting the movement of said carrier after the operation of said retarding means, substantially as specified. 70

2. In a machine of the character described, the combination of a movable carrier, with means adapted to be engaged by said carrier to retard the movement thereof, means for arresting the movement of said carrier after the operation of said retarding means, and means controlled by said arresting means to move said retarding means out of engagement with said carrier, substantially as 75 specified. 80

3. In a machine of the character described, the combination of a movable carrier, with means for arresting the movement of the carrier, a cylinder, a piston working within 85 the cylinder and adapted to be moved inwardly with respect thereto by the carrier, and means controlled by the carrier for retarding the inward movement of the piston whereby the movement of the carrier will be retarded, said last-named means being operative before the arresting means becomes effective, substantially as specified. 90

4. In a machine of the character described, the combination of a movable carrier, with 95 means for arresting the movement of the carrier, a cylinder adapted to contain a fluid and provided with an outlet port, a piston working within the cylinder and adapted to be moved inwardly with respect thereto by 100 the carrier to force the fluid out of the cylinder, and means controlled by the carrier for checking the flow of the fluid from the cylinder whereby the movement of the carrier will be retarded, said checking means 105 being operative before said arresting means becomes effective, substantially as specified.

5. In a machine of the character described, the combination of a movable carrier, with means for arresting the movement of the 110 carrier, a cylinder adapted to contain a fluid and provided with an outlet port, a piston working within the cylinder and adapted to be moved inwardly with respect thereto by the carrier to force the fluid out of the cylinder, a normally open valve to govern the flow of fluid from the cylinder, and means controlled by the carrier for actuating the valve to check the flow of fluid from the cylinder, whereby the movement of the carrier 115 will be retarded, said valve actuating means being operative before said arresting means becomes effective, substantially as specified. 120

6. In a machine of the character described, the combination of a movable carrier, with 125 means for arresting the movement of the carrier, a cylinder adapted to contain a fluid and provided with an outlet port, a piston working within the cylinder and adapted to be moved inwardly with respect thereto by 130

the carrier to force the fluid out of the cylinder, a normally open valve to govern the flow of fluid from the cylinder, and means controlled by the carrier after a predetermined inward movement of the piston for actuating the valve to check the flow of fluid from the cylinder, whereby the movement of the carrier will be retarded, said valve actuating means being operative before said arresting means becomes effective, substantially as specified.

7. In a machine of the character described, the combination of a movable carrier, with means for arresting the movement of the carrier, an oscillating cylinder, a piston working within the cylinder and adapted to be moved inwardly with respect thereto by the carrier, means for retarding the inward movement of the piston whereby the movement of the carrier will be retarded, said last-named means being operative before the arresting means becomes effective, and means actuated by said arresting means for controlling the oscillation of said cylinder, substantially as specified.

8. In a machine of the character described, the combination of a movable carrier, with means for arresting the movement of the carrier, an oscillating cylinder adapted to contain a fluid and provided with an outlet port, a piston working within the cylinder and adapted to be moved inwardly with respect thereto by the carrier to force the fluid out of the cylinder, means for checking the flow of the fluid from the cylinder whereby the movement of the carrier will be retarded, said checking means being operative before said arresting means becomes effective, and means actuated by said arresting means for controlling the oscillation of said cylinder, substantially as specified.

9. In a machine of the character described, the combination of a movable carrier, with a stop for arresting the movement thereof and movable into and out of the path of the carrier, and means actuated by the carrier during the normal operation thereof for automatically moving the stop into the path of the carrier after it has been moved out of said path, substantially as specified.

10. In a machine of the character described, the combination of a movable carrier, with a stop for arresting the movement of the carrier, said stop normally tending to move out of the path of the carrier, means for holding the stop in its operative position in the path of the carrier, means to render said holding means inoperative, and means for returning the stop to its operative position after said holding means has been rendered inoperative, substantially as specified.

11. In a machine of the character described, the combination of a movable car-

rier, with a stop for arresting the movement of the carrier, said stop normally tending to move out of the path of the carrier, means for holding the stop in its operative position in the path of the carrier, means to render said holding means inoperative, and automatically operated means for returning the stop to its operative position after said holding means has been rendered inoperative, substantially as specified. 75

12. In a machine of the character described, the combination of a movable carrier, with a stop for arresting the movement of the carrier, said stop normally tending to move out of the path of the carrier, means for holding the stop in its operative position in the path of the carrier, means to render said holding means inoperative, and means actuated by the carrier for returning the stop to its operative position after said holding means has been rendered inoperative, substantially as specified. 80

13. In a machine of the character described, the combination of a movable carrier, with a stop for arresting the movement thereof, a rocking lever upon which the stop is carried, said lever normally tending to rock to move the stop out of the path of the carrier, said lever having a portion adapted to move into the path of the carrier when the stop has been moved out of said path, whereby the carrier will engage said portion to rock the lever to move the stop into the path of the carrier, means for holding the lever in position with the stop in the path of the carrier, and means for rendering said holding means inoperative, substantially as specified. 90

14. In a machine of the character described, the combination of a movable carrier provided with a plurality of members, with a stop adapted to be engaged successively by said members to arrest the movement of the carrier, and means for retarding the movement of the carrier adapted to be actuated successively by said members, said retarding means being actuated by one of said members before another of said members engages said stop, whereby the movement of the carrier will be retarded before it is arrested, substantially as specified. 105

15. In a machine of the character described, the combination of a movable carrier provided with a plurality of equi-distantly spaced members, with a stop adapted to be engaged successively by said members to arrest the movement of the carrier, and means for retarding the movement of the carrier adapted to be actuated successively by said members, said retarding means being actuated by one of said members before another of said members engages said stop, whereby the movement of the carrier will be retarded before it is arrested, substantially as specified. 120

16. In a machine of the character described, the combination of a movable carrier, with means for arresting the movement thereof, means movable into and out of operative relation to the carrier for retarding the movement thereof before the arresting means becomes effective, and means for controlling the movement of the retarding means, substantially as specified.
- 10 17. In a machine of the character described, the combination of a movable carrier, with means for arresting the movement thereof, means movable into and out of operative relation to the carrier for retarding the movement thereof before the arresting means becomes effective, and means actuated by the arresting means for controlling the movement of the retarding means, substantially as specified.
- 15 18. In a machine of the character described, the combination of a movable carrier, with means for arresting the movement thereof, means for retarding the movement of the carrier before the arresting means becomes effective, and means controlled by said arresting means to move the retarding means out of engagement with the carrier, substantially as specified.
- 20 19. In a machine of the character described, the combination of a movable carrier, with a yielding stop for arresting the movement thereof, means adapted to be engaged by the carrier for retarding the movement thereof before the yielding stop becomes effective, and means controlled by the yielding stop to move the retarding means out of engagement with the carrier, substantially as specified.
- 25 20. In a machine of the character described, the combination of a movable carrier, with means for arresting the movement of the carrier, an oscillating cylinder, a piston working within the cylinder and having a piston rod adapted to be engaged by the carrier whereby the piston is adapted to be moved inwardly with respect to the cylinder, means for retarding the inward movement of the cylinder, and means actuated by the arresting means for controlling the oscillation of the cylinder, substantially as specified.
- 30 21. In a machine of the character described, the combination of a movable carrier, with a yielding stop for arresting the movement thereof and movable into and out of the path thereof, means actuated by the carrier for moving the arresting means into the path of the carrier after it has been moved out of said path, means movable into and out of operative relation with said carrier for retarding the movement thereof before said arresting means becomes effective, and means actuated by the arresting means as it is moved into and out of the path of the carrier to control the movement of the retarding means, substantially as specified.
- 35 22. In a machine of the character described, the combination of a movable carrier, with a yielding stop for arresting the movement thereof, an oscillating cylinder adapted to contain a fluid and provided with an outlet port, a piston working within the cylinder and having a piston rod adapted to be engaged by the carrier whereby the piston is adapted to be moved inwardly with respect to the cylinder to force the fluid out of the same, means for checking the flow of the fluid from the cylinder to retard the movement of the carrier, and means actuated by the yielding stop to oscillate the cylinder to move the piston rod out of engagement with the carrier, substantially as specified.
- 40 23. In a machine of the character described, the combination of a movable carrier, with means for arresting the movement thereof and movable into and out of the path thereof, means actuated by the carrier for moving the arresting means into the path of the carrier after it has been moved out of said path, means movable into and out of operative relation with said carrier for retarding the movement thereof before said arresting means becomes effective, and means actuated by the arresting means as it is moved into and out of the path of the carrier to control the movement of the retarding means, substantially as specified.
- 45 24. In a machine of the character described, the combination of a movable carrier, with means for arresting the movement of the carrier, an oscillating cylinder, a piston working within the cylinder and having a piston rod adapted to be engaged by the carrier whereby the piston is adapted to be moved inwardly with respect to the cylinder, means for retarding the inward movement of the cylinder, and means actuated by the arresting means for controlling the oscillation of the cylinder, substantially as specified.
- 50 25. In a machine of the character described, the combination of a movable carrier, with a yielding stop for arresting the movement thereof and movable into and out of the path thereof, means actuated by the carrier for moving the arresting means into the path of the carrier after it has been moved out of said path, means movable into and out of operative relation with said carrier for retarding the movement thereof before said arresting means becomes effective, and means actuated by the arresting means as it is moved into and out of the path of the carrier to control the movement of the retarding means, substantially as specified.

21. In a machine of the character de-
